INSULATED CONTAINER FOR A KEG OR THE LIKE

William F. Hunt, Louisville, Ky., assignor to Reynolds
Metals Company, Richmond, Va., a corporation of
Delaware

Filed May 22, 1963, Ser. No. 75,008

Term of patent 14 years

(CL D58—17)

FIG.1

FIG.2

Des. 198,596

PAGE 2

FIG.3

FIG.4

FIG. 5

FIG. 1 is a front perspective view of an insulated container for a keg or the like, showing my new design.

FIG. 2 is a rear elevation view thereof;

FIG. 3 is an exploded top perspective view thereof;

FIG. 4 is an elevational view of the end opposite that shown in FIG. 1; and

FIG. 5 is a top perspective view thereof with the cover removed.

The inside end wall opposite to that shown in FIG. 5 is identical thereto.

I claim:

The ornamental design for an insulated container for a keg or the like, as shown and described.
